GYRATORY CONE CRUSHER

Edgar B. Symons, Hollywood, Calif., assignor to
Nordberg Manufacturing Company, Milwaukee,
Wis., a Corporation of Wisconsin

Application October 20, 1930. Serial No. 489,734

12 Claims. (Cl. 83—10)

My invention relates to improvements in gyratory cone crushers and has for one object the provision of a crusher particularly adapted for fine reduction. Another object is the provision 5 of improved means for holding the crushing mantle in position upon the head. Another object is the provision of improved feed means. Other objects will appear from time to time in the course of the specification and claims.

10 I illustrate my invention more or less diagrammatically in the accompanying drawings, wherein—

Figure 1 is a vertical section;

15 Figure 2 is a top plan view of feed hopper and supporting means;

Figure 3 is a side elevation of parts shown in Figure 2 with parts broken away;

Figure 4 is a section on the line 4—4 of Figure 3;

20 Figure 5 is a detail of rack and pinion for making adjustments of feed hopper;

Figure 6 is a top plan view of a feed distributing plate;

25 Figure 7 is a section along the line 7—7 of Figure 6;

Figure 8 is a detail of securing means for feed plate.

Like parts are indicated by like symbols throughout the specification and drawings.

30 Referring to the drawings, A generally indicates any suitable base or foundation upon which the crusher may be mounted. A¹ indicates an outer main frame member laterally extending as at A² to provide an adequate supporting surface.

35 The frame member A¹ extends laterally at its upper edge to form the convex ring or seat A³ with its tapered sides A⁴ A⁵. A⁶ are radial supporting members which support the main bearing sleeve A⁷ with its upper housing or gear box extension A⁸ and its lateral drive housing extension A⁹.

40 B is a drive shaft upon the outer end of which is mounted the drive pulley B¹. The shaft B rotates in any suitable bearings B² in the removable bearing supporting sleeve B³. B⁴ is a beveled pinion in mesh with the gear B⁵ at the upper end of the eccentrically apertured sleeve B⁶. B⁷ is an anti-frictional lining of babbitt or the like positioned between the interior of the sleeve A⁷ and the exterior of the member B⁶. A similar anti-frictional babbitt B⁸ is positioned within the eccentric aperture B⁹ of the sleeve B⁶.

45 Positioned within the aperture B⁹ is the shaft C downwardly tapered, as shown in Figure 1,

to conform to the taper of the aperture B⁹. It includes a generally cylindrical upper portion C¹ of somewhat greater diameter, upon which is mounted the inner head member C², which includes a lower spherical convex bearing surface C³ resting upon the concave spherical bearing member C⁴ upon the gear box cover C⁵. The outer surface of the head member C² is generally conic as at C⁶ and terminates in a downwardly 60 apron C⁷ of generally cylindrical form. C⁸ C⁹ 65 indicate circumferential flanges formed upon the interior of the head member C², having respectively the spherical bearing surfaces C¹⁰ and C¹¹ opposed to the wiping members C¹² C¹³ which 70 may form part of the unitary wiping structure C¹⁴ upwardly thrust as by the spring C¹⁵ against the bearing surfaces C¹⁰ C¹¹.

75 Mounted upon the exterior conic surface C⁶ of the inner head member C² is the generally conic mantle, generally indicated as D. It has an inner conic surface D¹ opposed to the conic surface C⁶, and inwardly projecting lugs D² adapted to penetrate any suitable apertures in the head member C² to prevent relative rotation of the 80 mantle and head member. The outer crushing face of the mantle D includes a generally conic portion D³ which merges with an inwardly inclined or reduced portion D⁴. The lower edge of the mantle D conforms as at D⁵ to the cylindrical outer surface of the apron C⁷. The upper edge of the face D⁴ of the mantle is bounded or limited by a generally horizontal top face D⁶ which is broken by an inward ledge D⁷ in which seats a securing and feed distributing plate D⁸. 85 This plate D⁸ may be secured to the top C¹ of the gyratory shaft C, as by the bolts or screws D⁹ having heads D¹⁰. D¹¹ indicates a securing plate apertured about its periphery, as at D¹², to conform to the non-circular shape of the screw 90 heads D¹⁰, the rotation of which and the loosening of the screws and the plate D⁸ being thereby prevented. The locking plate D¹¹ is held in position as by the pin D¹⁴ and the locking member D¹³ thereupon. 95

100 The concave or bowl structure, which is opposed to the mantle D, is supported in the following manner: E generally indicates a ring recessed as at E¹ in general conformity with the flange A³ upon the frame A¹. The ring E is normally held seated upon said flange as by the coil springs E², the annular abutment E³ and the compression members E⁴ which pass upwardly through the flange A³ and the ring E and are 110

headed as at E⁵ with securing nuts E⁶ at their opposite ends below the abutment E³.

Positioned within the ring E is the bowl supporting member, generally indicated as G. It 5 includes the outer end generally cylindrical portion G¹ which is exteriorly screwthreaded as at G² to maintain a screwthreaded relationship with the opposed threads G³ upon the ring E. G⁴ is the bowl proper, herein shown as formed 10 integrally with the member G¹ and further connected therewith as by the webs G⁵. G⁶ is a bowl liner having an exterior generally conic face G⁷ conforming to the interior face of the bowl G⁴. The bowl G⁴ is cut away or apertured 15 as at G⁸, such apertures being formed to receive the hook shaped lugs G⁹ of the liner G⁶. G¹⁰ are U-bolts employed to secure feed lugs G⁹ and drawn up as by the nuts G¹¹ against any suitable abutments G¹². Note that the inner crushing 20 surface G¹³ of the liner G⁶ is throughout the greater part of its length parallel with, or only at a slight angle in relation to the opposed crushing surface of the mantle D. It may be somewhat outwardly flared, as at G¹⁴, in order to increase the diameter of the upper portion of the crushing zone defined by the opposed reduced 25 or outwardly inclined portion D⁴ of the mantle D.

Mounted in any suitable fashion upon the ring E are the upwardly extending supports H, upwardly screw-threaded as at H¹ to receive supporting nuts H² upon which ride supports H³ for the transverse frame structure H⁴. Mounted in such frame structure is a hopper H⁵ terminating 30 in a chute H⁶ preferably fixed in relation to the hopper. The chute is provided with a lower telescopic adjustable chute member H⁷, herein shown as exterior to the chute H⁶. It may include the upwardly extending slide H⁹ with which 35 is associated a rack H¹⁰ in mesh with a pinion H¹¹ mounted upon the transverse supporting frame H⁴. It will be understood that rotation of the pinion H¹¹, as by any suitable handle H¹², will raise or lower the movable chute portion H⁷ and 40 thus adjust the height of the chute in relation to the top plate D⁸ of the head. The chute member H⁷ is locked in position by means of the bolt H¹³ and set screws H¹⁴ H¹⁴.

J indicates a cylindrical housing or guard positioned upon the upper edge of the bowl member G⁴, and serving to limit and direct the flow of the material fed and to prevent its escape to the rear of the bowl.

A number of the details of the device herein shown, including the adjustments for the bowl and the oiling system, are not shown in detail herein or described since they do not of themselves form part of the present invention.

It will be realized that whereas I have described and shown a practical and operative device, that nevertheless many changes may be made in size, shape, number and distribution of parts without departing from the spirit and scope of my present invention. I therefore wish my drawings and description to be taken as in a broad sense illustrative or diagrammatic rather than as limiting me to my precise showing herein.

In connection with the description of the head and the phraseology of the claims, the head broadly includes the inner head member, the upper portion of the shaft upon which said inner head member is mounted, the mantle or effective crushing member which is mounted upon the inner head member, and the plate which serves 70 the double function of receiving the feed and of

holding the mantle in place. Similarly the surrounding bowl or concave broadly includes the outer bowl member and the bow shaped liner or effective crushing member which is mounted thereon.

In the claims it is stated that the head is provided with a generally flat top or a flat top portion. It will be understood, of course, that this language will not limit the application specifically to a flat top, as all that is necessary is that the peripheral portion of the top be sufficiently flattened to serve as a receiving member for the material to be crushed, from which it will move into the crushing cavity. As is clear from Figures 1 and 7 the flatness of the top is broken by the member D¹¹ with the bolt heads D¹⁰ and also by the member D¹³. Since these upward projections are positioned inwardly of the periphery or edge of the top of the cone they do not interfere with the operation of the device and it will be understood that an undisturbed movement from about the edge of the top of the head is an important function of the top of the head, which function is not interfered with by parts projecting upwardly from the top of the head at a distance inwardly of the edge sufficiently great to permit free escape of material over the edge.

In the claims is employed the statement that the generally flat top of the head lies generally within the plane of the upper edge of the effective crushing portion of the bowl. It is important that the top of the head be approximately at the top of the crushing member but some slight variation in either way does not interfere with the operation of the device. In fact, as shown in Figure 1, the edge D⁸ on the crushing side is shown just about at the plane of the upper edge of the effective crushing portion of the bowl, but the corresponding edge portion D⁶ on the discharge or right hand side of the cone or head as shown in Figure 1 is somewhat below the plane of the upper edge of the bowl liner. It will be understood that some variation in either direction is of little importance.

The use and operation of my invention are as follows:

In my gyratory crusher I employ a relatively steep cone, the angle of which is preferably greater than the angle of the proposed material delivered thereto, the crushing surface being defined by the mantle D and by the opposed bowl liner G⁶. The bowl or bowl liner forms a downwardly and outwardly inclined concave overhanging the cone or head. The parts are so proportioned that the head has a lateral travel upon its spherical bearing C³ very large in relation to the distance separating the opposed crushing surfaces at their moment of closest approach. In use, the crushing space between bowl and head has a cross section materially greater than that of the stream of material passing through and the head is withdrawn from the bowl, even after crushing impact for such a distance and at such a speed and at such an angle as to leave the material just crushed unsupported so that it drops freely by gravity downwardly away from the surface of the overhanging bowl to a lower portion of the cone.

The present crusher is primarily intended as a fine reduction crusher. The opposed crushing surface of the bowl and head, namely of the liner for the bowl and of the mantle for the head, may be made parallel substantially from top to bottom or throughout a substantial proportion of the area, from the bottom up. As shown in Fig-

- ure 1, they are flared apart at the upper part of the crushing zone, but from a crushing zone of relative small cross section in relation to the corresponding crushing zone of gyratory cone crushers adapted for coarse crushing. Through any suitable feeding means a relatively restricted volume of already finely divided material may be fed to the crushing zone, for example material of say three-quarters of an inch may be fed and 5 is broken up by repeated impacts of head against bowl, the material being reduced by successive crushing strokes, each terminating in a very close approach of head to bowl. Owing to the spherical mounting of the head, which gives the head the 10 effect, in action, as if it were suspended at a point where an apex above the top of the head, the actual carrying stroke of the head, increases progressively from top to bottom of the crushing zone. The material is finely reduced by the successive impacts, and may pack into clods or flakes 15 of fine particles. As these flakes are released, after each crushing impact, they may drop upon the cone and are broken up and again recrushed. The repeated packing, breaking and repacking 20 or flaking results in a maximum grinding or crushing of particle against particle and the end product may be practically of powder fineness. Owing to the spring release the head or cone and the bowl may be set to contact practically from 25 top to bottom and may be set to an extremely close approach, if desired.
- In supplying the feed I may employ the plate D⁸ as a species of distribution plate upon which is piled through the hopper H⁵ and the chute H⁶ and H⁷ the material to be crushed. By adjusting the vertical height of the chute H⁷ in relation to the plate D⁸, the volume of feed may be 30 controlled. Also adjustments to conform to the wear of the opposed bowl liner and cone mantle 35 may similarly be made. Also the supporting frame H⁴ may be vertically adjusted as a unit, as by rotation of the nuts H².
- Referring for example to Figure 1, it will be 40 seen that the feed plate D⁸ is positioned substantially below the center of the sphere defined by the opposed bearing members C³ and C⁴. This positioning of the feed plate permits or causes the material being crushed to be fed to the crushing zone at a level adjacent the top of the crushing zone. Thus the material begins its free fall 45 through the crushing zone at the top of the zone, and the acceleration of the fallen particles is insufficient to carry them far down into the crushing zone before they are caught by the first 50 crushing nip. If they were dropped from a level substantially above the top of the crushing zone, the gravitational acceleration would in many cases be sufficient to carry the material far down into the crushing zone before the first nip. The result 55 would be a lessening of the number of nips to which each particle is subjected, and a packing or concentration of the particles in the lower portion of the crushing zone.
- Another advantage of the position in which the 60 plate D⁸ is shown rests in a tendency of the material fed to it to move outwardly toward the crushing zone in response to the normal gyration of the head. There is no tendency of the material to build up on the plate or to move in a direction opposite to the direction of movement of the head, as is the case when the feed plate is 65 positioned above the center of the sphere defined by the bearing C³.
- I claim:
- 70 1. In a gyratory crusher, a normally fixed bowl,
- a crushing portion therefor, an upwardly conic crushing head, and a stationary bearing beneath the head adapted to form the support for the head, means for moving the crusher head on the bearing, the bearing being spherically concaved 80 from a center above the top of the crusher head to cause the movements of the crusher head to resemble the movements it would have if pivotally suspended at such point, said head being provided with an extended and generally flat top lying generally in the plane of the upper edge of the effective crushing portion of said bowl, and means for feeding material to the top of said head, and for confining such feed to said top. 85
2. In a gyratory crusher, a normally fixed bowl, 90 a crushing portion therefor, an upwardly conic crushing head, means for supporting said head and means for moving said head in a circular direction to cause the axis of the crusher head to describe a cone with its apex above the top of the crusher head, said head being provided with a generally flat top lying generally in the plane of the upper edge of the effective crushing portion of said bowl, and means for directing substantially the entire volume of feed directly to 95 the top of said head. 100
3. In a gyratory crusher, a normally fixed bowl, a crushing portion therefor, an upwardly conic crushing head, means for supporting said head and means for moving said head in a circular direction to cause the axis of the crusher head to describe a cone with its apex above the top of the crusher head, said head being provided with a generally flat top lying generally in the plane of the upper edge of the effective crushing 105 portion of said bowl, and means for directing substantially the entire volume of feed directly to 110 the top of said head, including a chute aligned with said top. 115
4. In a gyratory crusher, a normally fixed bowl, a crushing portion therefor, an upwardly conic crushing head, means for supporting said head and means for moving said head in a circular direction to cause the axis of the crusher head to describe a cone with its apex above the top of the crusher head, said head being provided with a generally flat top lying generally in the plane of the upper edge of the effective crushing 120 portion of said bowl, and means for directing substantially the entire volume of feed directly to 125 the top of said head, including a chute aligned with said top, and means for adjusting said chute vertically in relation to the top of the head. 130
5. In a gyratory crusher, a normally fixed bowl, a crushing portion therefor, an upwardly conic crushing head and means for gyrating it, said head being provided with a generally flat top, and means for directing substantially the entire volume of feed directly to the top of said head, including a chute aligned with said top and vertically adjustable in relation thereto, the feed receiving top of the head being positioned in substantially the plane of the top of the effective crushing portion of said bowl. 135
6. In a gyratory crusher, an upwardly conic crushing head and means for gyrating it, and a bowl surrounding said head, a crushing portion therefor, said head having a generally conic side face, a mantle mounted upon said conic side face, and means for holding said mantle in position upon said head, including a plate overlying a portion of the upper edge of said mantle and lying generally within the plane of the upper edge of the effective crushing portion of said bowl, and means for drawing said plate downwardly 140
- 145
- 150

- against the upper edge of the mantle, and means for delivering the material to be crushed to said plate, and for confining such feed to said plate.

7. In a gyratory crusher, an upwardly conic crushing head and means for gyrating it, and a bowl surrounding said head, a crushing portion therefor, said head having a generally conic side face, a mantle mounted upon said conic side face, and means for holding said mantle in position upon said head, including a plate overlying a portion of the upper edge of said mantle, and means for drawing said plate downwardly against the upper edge of the mantle, including a plurality of bolts in screwthreaded engagement with the head, and means for delivering the material to be crushed to said plate, and for confining such feed to said plate, said plate lying in the general plane of the upper edge of the effective crushing portion of said bowl.

20 8. In a gyratory crusher, a crushing head and means for gyrating it, and a bowl surrounding said head, said head having a generally conic side face, a mantle mounted upon said conic side face, and means for holding said mantle in position upon said head, including a plate overlying a portion of the upper edge of said mantle, and means for drawing said plate downwardly against the upper edge of the mantle, including a plurality of bolts in screwthreaded engagement with the head, and unitary means for preventing rotation of said bolts, including a locking plate apertured to conform to the shape of the heads of said bolts, and means for delivering the material to be crushed to said plate.

30 9. In a gyratory crusher, an upwardly conic crushing head and means for gyrating it, and a normally fixed bowl surrounding said head, a crushing portion therefor, the exterior surface of said head including a side portion corresponding generally to the form of a truncated cone, the head having a generally level top surface bounded by the upper edge of the truncated cone and lying generally in the plane of the top of the effective crushing portion of said bowl, the diameter of the level top exceeding the height of the

40 crushing zone between head and bowl, and means for delivering the material to be crushed to said level top surface, and for confining such feed to said plate.

5 10. In a gyratory crusher, an upwardly conic head including a generally conic crushing portion, a bowl including a crushing portion surrounding and overhanging the conic crushing portion of the head, said head being provided with a relatively flat top portion lying generally in the plane of the upper edge of the crushing portion of the bowl, and means for feeding the material to be crushed to said generally flat top portion and for confining such feed thereto.

15 11. In a gyratory crusher, a normally fixed bowl, a crushing portion therefor, an upwardly conic crushing head, the crushing portion of the bowl substantially overhanging said head, means for supporting said head and means for moving said head in a circular direction to cause the axis of the head to describe a cone the apex of which is above the top of the crusher head, the head being provided with a generally flat top lying generally in the plane of the upper edge of the effective crushing portion of the bowl, and means for feeding material to the top of the head.

20 12. In a gyratory crusher, a normally fixed bowl, a crushing portion therefor, an upwardly conic crushing head, the crushing portion of the bowl substantially overhanging said head, means for supporting said head and means for moving said head in a circular direction to cause the axis of the head to describe a cone the apex of which is above the top of the crusher head, the head being provided with a generally flat top plate lying generally in the plane of the upper edge of the effective crushing portion of the bowl, a mantle overlying said cone, the upper edge of said mantle underlying the outer edge of said plate, means for drawing said plate downwardly toward mantle and cone, and means for feeding material to the top of the head.
